[57] CLAIM

The ornamental design for a label applicator for a hand held label printer, as shown and described.

DESCRIPTION

FIG. 1 is a rear elevational view of a label applicator for a hand held label printer, showing my new design;

FIG. 2 is a top plan view thereof;

FIG. 3 is a front elevational view thereof;

FIG. 4 is a left side elevational view thereof;

FIG. 5 is a right side elevational view thereof; and,

FIG. 6 is a bottom plan view thereof.

The broken line showing of the hand-held labeler in FIG. 1 is for illustrative purposes only and forms no part of the claimed design.
